WIRE TRANSPOSITION REPAIR BRACKET

Henry J. Venus, Baker, Oreg.

Application August 2, 1947, Serial No. 765,672

5 Claims. (Cl. 174—33)

1

This invention relates to a bracket for use in effecting changes or repairs at a transposition point in parallel paired wires on poles, in telegraph and telephone circuits and the like.

In order to balance the electrical characteristics of communication circuits it is customary to transpose the wires of each two-wire circuit at intervals along the line by crossing and recrossing the wires so that the same wire does not remain continuously on the same side of the pair. The points at which the wires are crossed over are known as transposition points, and special cross-arm hardware is provided on the poles to keep the wires separated at such points. When any repair work is to be done at a transposition point, such as replacing a cross arm or broken insulators, or when it is desired to move a transposition point to a different cross arm or pole, it is necessary to hold the wires out of contact with each other while such work is being carried on. The wires ordinarily employed in such circuits are bare, and if they should contact one another the resulting short circuit is likely to throw certain automatic equipment out of order and put the line out of service. Heretofore any changes or repair work on such transposition points have been rendered very tedious and difficult by the problem of holding the wires apart while the work is being done.

The general object of the present invention is to provide a portable repair bracket to hold the wires apart while maintaining them in their crossed relation so that they may be temporarily pulled clear of the cross arm on which they had been supported. Other objects are to provide a repair bracket for the purpose described which may be applied to the wires while they are still supported on their cross arm insulators and which may be left on the wires until all the necessary repairs and changes have been completed and the wires have again been secured in permanent position on a cross arm, to provide a repair bracket which is particularly suited for use with conventional cross-arm hardware fixtures and to provide a bracket which may be used to move the transposition point either along the line to a different pole or laterally to shift the line to a new position on the right-of-way.

The invention comprises an open-center frame which is hinged on one side so that it may be opened and inserted between a pair of wires and around the cross-arm fixture carrying the insulators on which the wires are secured. The frame may thus be closed around the cross-arm fixture with the wires trained around guiding rollers on

2

the frame to hold them in the proper transposition relationship with one wire above the frame and the other wire beneath the frame. The invention further comprises a special tool which may then be used in conjunction with the frame to pull the wires free of the cross-arm insulators and allow them to be spaced and guided solely by the present repair bracket. The wires with the repair bracket supported thereby may then be pulled to one side or any other convenient position out of the way while the repair work is being carried on, there being no possibility of the wires coming into contact with each other to cause an interruption to service. The repair bracket may also be used to pull the line laterally to a different pole or up or down to a different cross arm on the same pole, and it may also be pulled along the line to change the position of a transposition point on the line. The wire supports on the repair bracket are preferably made in the form of rollers so that the bracket will travel quite freely along the line to move the transposition point as the bracket is being moved. While the present transposition bracket is intended primarily as a repair bracket to be used in the manner described, it may be left on the line as long as desired without interfering with service on the line, and it is capable of supporting itself in stable position at any point along the span between poles without any support other than the wires themselves.

Still other objects and advantages of the invention will become apparent to those skilled in the art as the invention is described in greater detail in the following specification with reference to the accompanying drawings illustrating a preferred embodiment of the invention. It is to be understood, however, that various changes may be made in the construction, proportion and arrangement of parts within the scope of the appended claims.

In the drawings:

Figure 1 is a perspective view of the present device in position at a transposition point on a pole cross arm;

Figure 2 is a plan view showing how the bracket is opened to pass around the insulator supports on the cross arm;

Figure 3 is a sectional view taken on the line 3—3 of Figure 1;

Figure 4 is a perspective view of a wire puller which is used with the present bracket to pull the wires on or off the cross-arm insulators;

Figure 5 is a plan view showing how two of the present repair brackets may be used to change a transposition on a cross arm; and

Figure 6 is a plan view showing how the bracket may be used to move the wires laterally from one pole to another.

The present repair bracket is particularly adapted for use with a cross-arm fixture of the type illustrated in Figures 1 and 2. The numeral 10 designates a cross arm on a pole. Bolted on top of the cross arm is a plate 11 having welded thereto a pair of U-shaped rods 12 and 13 carrying the usual insulators 14, 15, 16, and 17. It will be observed that the insulators 15 and 17 stand higher above the cross arm than the insulators 14 and 16. A bare wire 20 is carried on the high insulators 15 and 17 to cross over several inches above a bare wire 21 on the low insulators 14 and 16 to form a transposition point on the line. Wire ties, not shown, are ordinarily wrapped around the grooves in the insulators to tie the conductors 20 and 21 in place. The structure thus far described illustrates a conventional transposition point in telegraph and telephone circuits and the like. This particular arrangement of the wires is designated as a "left over" transposition because the left wire 20 crosses over the right wire 21. When it is necessary to replace any of the insulators 14 to 17, or the cross arm 10, or to move the circuit to a different cross arm, such operation must be carried out without allowing the bare wires 20 and 21 to come into contact with each other.

The features of the present invention are embodied in the rectangular transposition repair bracket designated generally by the numeral 25. This bracket comprises a two-piece rectangular frame of wood or other insulating material hinged at 26 for insertion beneath the wire 20 and above the wire 21 to encircle the cross-arm fixture in the manner shown in Figure 2. When the frame 25 is closed together around the fixture, as shown in Figure 1, the wire 20 will be disposed wholly on the top side of the frame and the wire 21 will be disposed wholly on the under side of the frame. Guides 27 are provided at the joint in the frame to hold the two meeting parts in proper alignment. The opposite sides of the frame are equipped with eye bolts or the like 28 for the attachment of a rope to pull the device away from the pole when the line is to be shifted laterally. The opposite sides of the frame are also provided with a series of holes 29 to receive the wire pulling tool shown in Figure 4 which will presently be described.

In the illustrated embodiment, the frame 25 is an open-center rectangle slightly longer than it is wide. On each of the two short sides of the rectangular frame are mounted a pair of bolts 30 having plates 31 to serve as braces and guards in cooperation therewith. The bolts 30 are preferably spaced approximately the same distance apart as the rods 12 and 13 on the cross-arm fixture with which the device is to be used, and on these bolts at the four corners of the frame and on opposite sides thereof are mounted eight insulating rollers to guide and support the wires 20 and 21. The rollers on the top side of the frame are designated by the numerals 34 to 37 inclusive, and the corresponding rollers on the under side of the frame are designated by the same numbers with the subscript *a* added. Thus the top wire 20 on the insulators 15 and 17 engages the top rollers 35 and 37 and the lower wire 21 on the insulators 14 and 16 engages the rollers 34a and 36a. The separation of the wires on the opposite sides of the frame of the bracket 25 is also clearly shown in Figure 3 where it will be

observed that the insulating rollers 35a and 36a are not used in a "left over" transposition. Likewise, the rollers 34 and 37a are not used in this transposition. The four rollers just mentioned would be used in a "right over" transposition, however, in which case the four rollers 34a, 35, 36a and 37 would be unnecessary.

The frame 25 is of sufficient length to place the wire-engaging rollers a little distance away from the pole insulators when the frame is inserted between the wires as shown in Figure 2. As hereinabove pointed out, the lateral spacing of the wire-engaging rollers is approximately the same as the lateral spacing of the pole insulators whereby the rollers 35 and 36a may readily be placed between the wires in the manner shown. As the frame is closed around the pole insulators it may be moved to the left in Figure 2 to space rollers 34a and 37 several inches to the left of pole insulators 14 and 17. Then wire 20 is moved by hand over the end of guard 31 to engage roller 37, and wire 21 is moved over the end of another one of the guards 31 to engage roller 34a, as shown in Figure 1. The wires 20 and 21 are thus disposed outside the transposition frame rollers and may then be removed from the pole insulators without danger of coming into contact with each other.

After the wire ties holding the wires 20 and 21 to the insulators 14 to 17 have been clipped off, the wire-pulling tool 40 shown in Figure 4 is used to pull the wires off these insulators to leave them guided solely by the rollers on the bracket 25. The tool 40 has a pivot stud 41 on one end to fit in one of the holes 29 in a convenient position so that a hook 42 on chain 43 may be hooked over the wire to pull it out of the groove in its insulator. The handle on this tool is made long enough to provide the necessary leverage so that the taut wire may easily be pulled clear and free of its insulator. The tool 40 is not attached to the bracket 25 in any way but may be freely applied to any of the holes 29 to serve its purpose. This tool is also useful in putting the wires back on the cross arm insulators when the wires are under considerable tension.

When the wires have been removed from the cross-arm fixture in the manner described, the bracket 25 and the wires may then be moved together according to the nature of the work to be done. The wire tension holds the two sides of the frame of the bracket tightly together and maintains the bracket in stable position supported solely by the wires without any tendency to twist the wires or bring them together to produce a short circuit. If it is only necessary to replace the cross arm or certain of the insulators 14 to 17, the bracket 25 may be merely pulled up or down or to one side to move the wires out of the way while the work is being done. Figure 6 shows how a two-wire circuit may be pulled to one side to be transferred to a different pole. In this figure the wires 20 and 21 originally carried on the cross arm 10 are being moved over to the cross arm 10a on another pole. By attaching a rope 45 to one of the eye bolts 28 the bracket 25 is pulled over laterally to the new pole to bring the wires into their new positions.

Figure 5 illustrates the manner of moving a transposition point or points along the line from one pole to the next. In this view the transposition point A has just been removed from the cross arm 10 and is being pulled to the left by rope 46 on bracket 25a to be positioned at the next pole

on the line. It will be noted that the transposition point A is a "left over" transposition as shown in Figures 1 and 2. At the same time a second transposition bracket 25b, identical with the bracket 25a and with the bracket 25 in the other views, is being used to move a "right over" transposition point B down to the cross arm 10, this bracket being pulled along in a similar manner by a rope 47. There is, of course, no limitation on the distance which the transposition points A and B may be moved, as they may be pulled past any pole along the line. If the transposition point B is to be stationed at the cross arm 10, it will be apparent that the cross-arm fixture will have to be changed, because in such case the insulators 14 and 16 would have to be the high insulators and the insulators 15 and 17 would have to be the low insulators.

In Figure 5, reference numerals are applied only to those repair bracket rollers which are engaging one of the wires, the reference numerals being omitted from those rollers which are not in use. Thus, in the bracket 25a containing the "left over" transposition A, the wire 20 passes around the rollers 35 and 37 on the top side of the frame and the wire 21 passes around the rollers 34a and 36a on the under side of the frame. In the "right over" transposition B contained in the frame 25b the wire 20 passes around the rollers 34 and 36 on the top side of the frame and the wire 21 passes around the rollers 35a and 37a on the under side of the frame.

It is apparent also that if sufficient slack may be pulled in the wires, two of the repair brackets may be used as shown in Figure 5 to form two new transportation points in a span which did not previously have a transposition point. After being formed in this manner the two new transposition points A and B may then be pulled apart for any distance on the line to suitably placed poles. Still other uses for the present device will occur to persons skilled in the art.

The rollers should roll freely on the bolts 30 and suitable bearing elements may be included if desired, although in practice the provision of any special bearings is not found to be necessary. These rollers are shown as made of insulating material such as porcelain, but they may be of metal because the non-conducting frame 25 insulates the mountings for the rollers in any event. This is an important feature of the present construction because there should be no possibility of short circuit by contact of a wire either with a bolt 30 or a guard 31. Even if insulating rollers are used, it is still desirable that there be no possibility of short circuit should one of the rollers break in use.

Having now described my invention and in what manner the same may be used, what I claim as new and desire to protect by Letters Patent is:

1. A transposition repair bracket comprising an open center frame of insulating material, a pair of longitudinal joints in said frame, a hinge on one of said joints, guides on the other joint to register the two parts of the frame at the joint, a plurality of conductor guide elements on opposite sides of the frame to hold a pair of conductor wires in transposition relation, and a series of pivot holes along the sides of said frame to receive a wire pulling lever, the center opening in said frame having a width exceeding

the lateral spacing of said guide elements so that said frame may be placed around a cross arm fixture without removing the wires therefrom.

5 2. A transposition repair bracket comprising an open-center frame, a pair of joints in said frame for opening the frame to encircle a cross-arm fixture between the conductors at a transposition point in a pair of conductors, conductor guide elements on opposite sides of said frame 10 in positions to engage said conductors on both sides of the fixture and hold said conductors in spaced transposition relation for removal from the fixture, a wire pulling lever, and means for pivotally engaging said lever at a plurality of 15 points on said bracket.

3. A transposition repair bracket for removing a transposition point in a pair of conductor wires from wire supports on a cross arm fixture where one conductor crosses above the other, comprising a jointed frame having an open center of sufficient size to encircle the cross arm fixture between the wires to be removed, and pairs of wire-engaging elements on opposite ends of said frame 20 spaced longitudinally of the wires a greater distance apart than the longitudinal spacing of the wire supports on said fixture, the wire-engaging elements of each pair being spaced laterally approximately the same distance apart as the lateral spacing of the wire supports on said fixture.

25 4. A transposition repair bracket comprising an open-center elongated rectangular frame, a pair of joints in said frame for opening the frame to encircle a cross arm fixture or the like between the wires at a transposition point in a pair of conductor wires mounted on wire supports on said fixture, and pairs of wire-engaging elements on opposite ends of said frame spaced longitudinally of the wires a greater distance apart than the longitudinal spacing of the wire supports on 30 said fixture, the wire-engaging elements of each pair being spaced laterally approximately the same distance apart as the lateral spacing of the wire supports on said fixture.

35 5. A transposition repair bracket for removing a transposition point in a pair of conductor wires from wire supports on a cross arm fixture where one conductor crosses above the other, comprising an elongated rectangular frame having an open center of sufficient size to encircle the cross 40 arm fixture between the wires to be removed, joints in the ends of said frame for opening the frame to encircle said cross arm fixture, a hinge on one of said joints, and pairs of wire-engaging elements on opposite ends of said frame spaced longitudinally of the wires a greater distance 45 apart than the longitudinal spacing of the wire supports on said fixture, the wire-engaging elements of each pair being spaced laterally approximately the same distance apart as the lateral spacing of the wire supports on said fixture.
